UNITED STATES PATENT OFFICE.

DANA DWIGHT BARNUM, OF WORCESTER, MASSACHUSETTS, AND HENRY A. CARPENTER, OF SEWICKLEY, PENNSYLVANIA, ASSIGNEES TO RITER-CONLEY MANUFACTURING COMPANY, OF PITTSBURGH, PENNSYLVANIA, A CORPORATION OF NEW JERSEY.

APPARATUS FOR GENERATING GAS.

1,091,111.

Specification of Letters Patent. Patented Mar. 24, 1914.

Application filed December 2, 1910. Serial No. 595,226.

To all whom it may concern:

Be it known that we, DANA DWIGHT BARNUM and HENRY A. CARPENTER, citizens of the United States of America, and residents of Worcester, in the county of Worcester, State of Massachusetts, and Sewickley, in the county of Allegheny, State of Pennsylvania, respectively, have jointly invented a new and useful Improvement in Apparatus for Generating Gas, of which improvement the following is a specification.

The prime object of our invention is to provide a new and improved apparatus for generating gas in which a multiplicity of pipes leading from the various retorts to a gas take-off, or main, are dispensed with, thereby greatly reducing the expense of construction; obviating the inconveniences due to the presence of said pipes and the disadvantages in the method of operating the same.

In the accompanying drawing, which illustrates an application of our invention, Figure 1 is a front elevation of a gas generating apparatus constructed in accordance with our invention, Fig. 2 a section, the section being taken on line 2—2 of Fig. 1, and Fig. 3 a vertical section taken on line 3—3 of Fig. 1.

Referring to the drawings, 1—1 designate 30 retorts disposed in a plurality of gas benches.

2—2 designate vertically disposed stand pipes, preferably rectangular in cross section, although they may be tubular.

35 In the embodiment of our invention as illustrated, the lower ends of the said stand pipes are connected to and communicate with a gas take-off 3, which is provided with lids 4, through which the same may be cleaned, the said lids being held in place by means of clamps 6. The said stand pipes are connected to the various retorts by means of lateral branches 7. The stand pipes are also connected to the rear buck staves (not 45 shown) of the benches by means of rods 8.

As illustrated, and as preferred, the retorts 1 are arranged in rows with a stand pipe, or a vertically extending gas delivery pipe 2, arranged between two adjacent rows and in common communication through the 50 branch pipes 7 with a plurality of retorts of the two adjacent rows. The stand pipe being connected with the take-off pipe 3 permits an uninterrupted flow of gas from the retorts to and through the gas take-off, or 55 main.

What we claim is:

1. In an apparatus for generating gas, the combination with two rows of superposed parallel retorts, of a stand pipe located between the two rows of retorts and between the vertical planes passing through the longitudinal axes of the retorts in each row and in common communication with the retorts of the two rows, and a take-off pipe in 65 communication with the stand pipe.

2. In an apparatus for generating gas, the combination with two gas benches arranged side by side, a retort in each bench, said retorts extending back from a common face 70 of the generator, a stand pipe located between the vertical planes passing through the longitudinal axis of each of the said retorts, and means connecting the stand pipe with the retort of each bench. 75

In testimony whereof, we have hereunto signed our names in the presence of two subscribing witnesses.

DANA DWIGHT BARNUM.
HENRY A. CARPENTER.

Witnesses to the signature of Dana Dwight Barnum:

RUFUS B. FOWLER,
PENELOPE COMBERBACH.

Witnesses to the signature of Henry A. Carpenter:

CLARENCE A. WILLIAMS,
